UNITED STATES PATENT OFFICE.

JAMES M. CONNER, OF NEW YORK, N. Y.

DESIGN FOR TYPE.

SPECIFICATION forming part of Design No. 17,128, dated February 22, 1887.

Application filed December 17, 1886. Serial No. 921,902. Term of patent 14 years.

To all whom it may concern:

Be it known that I, JAMES M. CONNER, of the city, county, and State of New York, have invented a new Design for a Font of Printing-Type, of which the following is a specification.

The nature of my design is clearly shown in the accompanying typographic impression, to which reference is made; and it consists of a text letter ornamented by a series of flourishes 15 below the letters and a series of spear-head-like ornaments crossing the letters vertically and proceeding from a line, as shown, the cross ornament of the A extended upon the left of the up-and-down portion of the letter 20 and ornamented by a light line curving to the left and terminating in the dot, the cross-line of the A also extended upon the right of the up-and-down portion and ornamented by a light line curving to the right and terminating in the dot, a similar ornamentation found in the cross-line of the E and Z, the upper 25 right ornament of the C and H consisting of a figure formed of the slightly-curved lines, as shown, somewhat resembling a rhomb, and placed transversely, followed by a light line with dot termination. The upper 30 right-hand termination of the E, F, G, K, U, V, and W consists of the figure formed of the slightly-curved lines, as shown, somewhat resembling a rhomb, and placed transversely.

Having now set forth my invention, I claim—

The design for a font of printing-type, as shown and described, the same consisting of a text letter ornamented by a series of flourishes 35 below the letters and a series of spear-head-like ornaments crossing the letters vertically and proceeding from a line, as shown, the cross ornament of the A extended upon the left of the up-and-down portion of the letter 40 and ornamented by a light line curving to the left and terminating in the dot, the cross-line of the A also extended upon the right of the up-and-down portion and ornamented by a light line curving to the right and terminating in the dot, a similar ornamentation formed in the cross-lines of the E and Z, the upper 45 right ornament of the C and H consisting of a figure formed of the slightly-curved lines, as shown, somewhat resembling a rhomb, and placed transversely, followed by a light line with dot termination, and the upper right-hand termination of the E, F, G, K, U, V, and W consisting of a figure formed of the slightly-curved lines, as shown, somewhat resembling 50 a rhomb, and placed transversely.

JAMES M. CONNER.
